United States Patent Office.

FRANKLIN ROOT, OF HARTFORD, CONNECTICUT.

Letters Patent No. 106,211, dated August 9, 1870.

IMPROVED CURTAIN-FIXTURE.

The Schedule referred to in these Letters Patent and making part of the same.

I, FRANKLIN ROOT, of Hartford, in the county of Hartford and State of Connecticut, have invented certain Improvements in Curtain-Fixtures, of which the following is a specification.

Nature and Objects of the Invention.

One part of my invention relates to the manner of attaching the metal "spools" or pulleys to the ends of the roller usually fastened at the top of the window, and the object is to so fasten thereto certain collars or flanges that the proper adjustment of another roller, which depends by cords from said collar, may readily be made.

Another part of my invention relates to an apparatus whereby a secondary roller, bearing the curtain, and which may be made to rise and fall at will, thus allowing the curtain to be let down at the top, as well as raised at the bottom, may also be made, at any point of dependence, to roll the curtain up from the bottom.

My invention has but these two parts.

Description of the Accompanying Drawing.

Figure 1 is a front view of a window with my invention attached.

Figure 2 is a detached sectional view of the pulley or spool attached to the end of the movable or secondary roller.

Figure 3 is a detached sectional view, showing the method of attaching the "spools" or pulleys to the ends of the fixed roller.

General Description.

A is the frame of the window.

B is the fixed roller turning in the bearings a a.

To one end of the roller B is attached a metal spool or pulley, shown in section in fig. 3, composed of two pieces, b, with a screw attached, screwing into the end of the roll, and the collar or flange c, fitting on over the screw, which is fastened on tightly by driving the screw into the wood.

This device has two grooves for cords, one at d and one at e.

In the groove d runs an endless cord, x, running also around a pulley, f, at the bottom of the window, which is fastened to the frame by a spring, so as to keep the cord taut. This cord will, of course, revolve the roller B one way or the other, as the cord is pulled.

The pulley upon the opposite end of the roller B from the one just described is made in nearly the same manner. The difference is that it has upon it the loose pulley b', which just fits up against a thin flange, which forms one side of the groove c. The

flange or collar c' is fastened on precisely as is the collar c.

In the grooves c and c' run the cords g g.

These cords are fastened by running them through the collars c and c', where they are knotted, the knots just fitting into cavities in the ends of the roller B.

The hole in the collar c and the cavity for the knot are shown at h, in fig. 3.

From the ends of the cords g g depend the movable roller C, which must, of necessity, be kept level. Hence it is necessary that the cords g g should commence to wind at just the same time.

This is effected by having the collars c and c' loose from the screws which fasten them to the roller, so that the knots can be placed exactly in the right places to effect such adjustment.

To the lower end of the cords g g are attached hanging bearings o o, in which the ends of the roller C turn freely.

The curtain D is attached to this movable roller C, and it will be readily understood that, as the roller B is made to revolve by means of the cord x, the roller C will be moved up or down, and the curtain let down or raised at the top accordingly.

Around the loose pulley b', and down around the pulley f', runs the endless cord x', kept taut in the same manner as the cord x.

This cord takes a single turn around the pulley i, attached to the roller C, so as to turn the roller when the cord is pulled up or down.

It is thus obvious that, no matter at what point the roller C is suspended, the curtain can be rolled up or let down at the bottom, by means of the cord x', without at all affecting the status of the roller C.

Not only this, but, when the roller C is moved up or down by means of the cord x, the cord x' will cause it to revolve with just the right direction and motion to roll or unroll the curtain at the top, so that the status of the bottom of the curtain will not be affected.

By this arrangement the curtain can be rolled up or down from the bottom or the top, or from any point in the line of suspension—a most convenient arrangement.

The groove in the periphery of the pulley i is shown in fig. 2, and its shape makes it certain that the cord will not slip on the pulley.

Many of the parts not claimed herein are claimed in former applications of mine, but, with respect to the purposes of this application, all those parts are old which are not specifically claimed herein.

I expressly disclaim the use of the cord x', when arranged as described, and applied to the rolling of a

fixed curtain-roll. It is only when applied to a roll made movable in manner and form, as is the roller C, that I claim an invention.

Claims.

I claim as my invention—

1. The combination of the fixed roll B, the collar c, and the pulley b, constructed substantially as described, for the purposes set forth.

2. The combination of the parts mentioned in the preceding clause with the movable roll C, the pulley i, cord z', and loose pulley b', constructed substantially as described, for the purposes set forth.

Dated November 29, 1869.

FRANKLIN ROOT.
